UNITED STATES PATENT OFFICE.

ALBERT BOVY, OF BERCHEM-STE.-AGATHE, BELGIUM.

FOLDING BOX.

1,324,873.

Specification of Letters Patent. Patented Dec. 16, 1919.

Application filed June 2, 1919. Serial No. 301,314.

To all whom it may concern:

Be it known that I, ALBERT BOVY, a subject of the King of the Belgians, residing at 111 Rue Openveld, Berchem-Ste.-Agathe,

5 Province of Brabant, Kingdom of Belgium, have invented a new and useful Improvement in or Relating to Folding Boxes; and I do hereby declare the following to be a full, clear, and exact description of the same.

10 This invention relates to folding boxes; and its object, stated briefly, is to provide an improved article of the type indicated which, contrary to the usual construction, may be made with one, two or even three 15 of its side walls of multiple thickness, thereby affording sufficient strength to enable said walls to sustain the weight of articles placed on top of the box.

The invention resides primarily in the 20 particular construction and arrangement of the component parts of the box in such a manner as to produce the multiple-ply feature above referred to and, also, to permit the assembling and connecting of said parts 25 easily and comparatively rapidly, and without requiring the services of a skilled operator.

Several embodiments of the invention are 30 illustrated in the accompanying drawing, in which:

Figure 1 is a perspective view of the body member of the box;

Fig. 2 is a plan view of the blank which is utilized in the construction of the box to 35 form a folding strip;

Fig. 3 is a plan view of a cover blank adapted to form the top, bottom, front and rear walls of the box;

Fig. 4 is a vertical cross-section of a box 40 in which a single reinforcing interlock only is employed;

Fig. 5 is a perspective view showing the arrangement employed to provide a double reinforcing interlock between the folding strip and the body member, only one of the interlocks being completed;

Fig. 6 is a vertical cross-section of a completed box involving the arrangement represented in Fig. 5;

50 Fig. 7 is a perspective view of a modified form of body member, the ends of which are left open;

Fig. 8 shows a detail of the cover blank;

Fig. 9 is a perspective view of a partially 55 completed box, utilizing the body member illustrated in Fig. 7;

Fig. 10 shows a further stage in the construction of the box;

Fig. 11 is a vertical cross-section of the completed box; and

60 Figs. 12 to 16 show diagrammatically various other ways in which the cover blank may be constructed.

Referring more particularly to the drawing, 1, 2 and 3 indicate the three main parts 65 or members of the box, viz: the folding strip, the body member and the cover blank, respectively, all of which are constructed of suitable sheet material. The body 2 forms the vertical walls of the box and comprises 70 a skeleton rectangle, the ends of the strip or blank from which this member is constructed being either joined together to completely close the rectangle, as in Fig. 1, or left spaced as in Fig. 7, depending largely 75 upon the size of box desired. The folding strip 1 is provided at its ends with flaps 1', which are utilized in the manner illustrated in Figs. 5 and 6. The cover flap 3 likewise has the form of an elongated strip or blank 80 of appropriate dimensions, which may be transversely scored or otherwise marked (as is also the case with the folding strip represented in Fig. 2) to define its main sections. Four of these sections, indicated at 3', 3², 3³ 85 and 3⁴, and respectively constituting, either partly or wholly, the front, bottom, rear and top walls of the box are here shown; and in addition, the strip or blank may also comprise an extension or flap 3⁵, forming a continuation of the section 3⁴, for coaction with the front or right-hand section or member 3' of the blank.

The box represented in Fig. 6 is constructed substantially as follows: The cover strip 95 3 is folded along its score lines or the like and applied to the body 2 in such a manner that the cover section 3⁴ will overlie the top of the body, the section 3³ will fit against the inner face of the rear wall of the body, 100 the section 3² will underlie the bottom edge of the body, and the section 3' will be disposed exteriorly of the body and opposite the outer face of the front wall thereof. The folding strip 1 is thereafter passed beneath the partially-completed box in a direction at right angles to the cover blank or strip, and its end flaps 1' folded first upwardly against the outer faces of the side walls of the body and then over and downwardly against the inner faces of said walls 105 in the manner indicated in Fig. 5. The 110

front member 3' of the cover blank is thereupon successively folded first upwardly against the outer face of the front wall of the body, and then over the upper edge of 5 that wall and downwardly against its inner face, so as to straddle or interlock with it in much the same way that the side walls of the body are straddled or interlocked by the end flaps 1'. The cover member 3⁴ is then 10 bent down into place, and its extension flap 3⁵, which has previously been folded downward at right angles, is engaged with the in-turned portion of the front member 3', as will be understood from Fig. 4.

15 In the construction shown in Fig. 4, however, the bottom portion 3² of the blank 3 underlies instead of overlies the main portion 1 of the folding strip, which latter is placed within the partially-completed box 20 in the ordinary way, the two constructions being otherwise the same.

To support the flap 3⁵, there is provided a lug or tongue 4, which is preferably disposed centrally and transversely of the 25 member 3' of the blank or strip 3 and which may be formed by slitting the free edge of that member (Figs. 8 to 11), though it may, if desired, be constructed in various other ways. In Figs. 4 and 11, this tongue is 30 bent upwardly and backwardly against the innermost section or fold of the member 3' so as to lie immediately beneath flap 3⁵ and hold it in place, as will be understood; while in Fig. 12, it is formed by a separate piece 35 or part which is secured obliquely to the aforesaid section or fold in position to effect the desired engagement with the flap 3⁵. In Fig. 13, the tongue is shown as formed as an extension of said fold or section which 40 is bent back into oblique relation thereto and which acts in the same manner as the tongue in Fig. 12. In Fig. 14, the tongue is bent in the same way as in Fig. 13, but is long enough to form a recess or pocket into which 45 the flap 3⁵ projects, the free end or terminal of the tongue being bent laterally outward so as to underlie the top member 3⁴. Much the same construction is also adopted in Fig. 16 excepting that the pocket or recess is of 50 U-section instead of V-section. In Fig. 15, the construction is generally similar to that shown in Fig. 11, but the tongue in this case forms an extension or prolongation of the section or fold of the member 3', instead of being produced by slitting said section.

Having fully described my invention what I claim and desire to secure by Letters Patent is:

1. In a folding box, the combination of 60 an open or skeleton body member; and a cover strip coöperating with said body to form the bottom, rear, top and front walls of the box, said strip comprising a horizontal member extending across the opposite lower edges of the body to close the bottom

thereof, a vertical member extending upwardly against the inner face of the rear wall of the body, a movable horizontal member extending from the upper end of said vertical member and terminating at the 70 front wall of the body so as to close the top of the body, and a vertical member extending upwardly from the front end of the bottom member along the outer face of the front wall of the body and having its upper 75 portion folded over the upper edge of said front wall and bent inwardly and downwardly against the inner face of that wall for nearly the entire height thereof; substantially as described.

2. In a folding box, the combination of an open or skeleton body member; and a cover strip coöperating with said body to form the bottom, rear, top and front walls of the box, said strip comprising a horizontal member 80 extending across the opposite lower edges of the body to close the bottom thereof, a vertical member extending upwardly against the inner face of the rear wall of the body, a movable horizontal member extending from the upper end of said vertical member and terminating at the front wall of the body so as to close the top of the body, and a vertical member extending upwardly from the front end of the bottom 85 member along the outer face of the front wall of the body and having its upper portion folded over the upper edge of said front wall and bent inwardly and downwardly against the inner face of that wall 90 for nearly the entire height thereof; said top member having an extension flap at its free front edge which projects downwardly into the interior of said body, and the in-folded portion of said front member having 95 means for supporting said flap; substantially as described.

3. In a folding box, the combination of an open or skeleton body member; a cover strip coöperating with said body to form the 110 bottom, rear, top and front walls of the box, said strip comprising a horizontal member extending across the opposite lower edges of the body to close the bottom thereof, a vertical member extending upwardly against the inner face of the rear wall of the body, a movable horizontal member extending from the upper end of said vertical member and terminating at the front 115 wall of the body so as to close the top of the body, and a vertical member extending upwardly from the front end of the bottom member along the outer face of the front wall of the body and having its upper portion folded over the upper edge of said front wall and bent inwardly and downwardly against the inner face of that wall for nearly the entire height thereof; and a folding strip 120 arranged at right angles to the cover strip and having its bottom portion disposed 125

against the under face of the bottom member of said cover strip and its end portions bent vertically upward against the outer faces of the side walls of the body and folded 5 over the upper edges of said side walls and then bent inwardly and downwardly against the inner faces thereof; substantially as described.

4. In a folding box, the combination of an 10 open or skeleton body member; a cover strip coöperating with said body to form the bottom, rear, top and front walls of the box, said strip comprising a horizontal member extending across the opposite lower edges of 15 the body to close the bottom thereof, a vertical member extending upwardly against the inner face of the rear wall of the body, a movable horizontal member extending from the upper end of said vertical member 20 and terminating at the front wall of the body so as to close the top of the body, and a vertical member extending upwardly from the front end of the bottom member along the outer face of the front wall of the body 25 and having its upper portion folded over

the upper edge of said front wall and bent inwardly and downwardly against the inner face of that wall for nearly the entire height thereof; said top member having an extension flap at its free front edge which projects downwardly into the interior of said body, and the in-folded portion of said front member having means for supporting said flap; and a folding strip arranged at right angles to the cover strip and having its bottom portion disposed against the under face of the bottom member of said cover strip and its end portions bent vertically upward against the outer faces of the side walls of the body and folded over the upper edges of 30 said side walls and then bent inwardly and downwardly against the inner faces thereof, substantially as described.

In testimony whereof, I have signed my name to this specification in the presence of 40 two subscribing witnesses.

ALBERT BOVY.
